(**) Term: **15 Years**

CLAIM

(21) Appl. No.: **29/696,783**

The ornamental design for a support for mobile phones and tablets, as shown and described.

(22) Filed: **Jul. 1, 2019**

DESCRIPTION

(51) **LOC (13) Cl. 14-03**

FIG. 1 is a perspective view of a support for mobile phones and tablets showing my new design;

(52) **U.S. Cl.**

FIG. 2 is a front elevational view thereof;

USPC **D14/253; D4/447**

FIG. 3 is a rear elevational view thereof;

(58) **Field of Classification Search**

FIG. 4 is a left side elevational view thereof;

USPC D14/251-253, 447, 452, 432-434, 440;

FIG. 5 is a right side elevational view thereof;

D12/415; D3/218; D8/349, 363

FIG. 6 is a top plan view thereof;

CPC H04M 1/02; H04M 1/04; B60R 11/02;

FIG. 7 is a bottom plan view thereof;

F16M 11/00; F16M 11/04; F16M 11/06

FIG. 8 is another perspective view thereof;

See application file for complete search history.

FIG. 9 is a front perspective view in a use state thereof; and,

(56) **References Cited**

FIG. 10 is a rear perspective view in a use state thereof.

U.S. PATENT DOCUMENTS

The broken lines shown are included for the purpose of

D815,104 S * 4/2018 Bertelle D14/447
